Primary Examiner — Michelle E. Wilson*Assistant Examiner* — Richard E Yenchesky(74) *Attorney, Agent, or Firm* — Leydig, Voit & Mayer, Ltd.(57) **CLAIM**

The ornamental design for a nozzle for floor cleaner, as shown and described.

DESCRIPTION

FIG. 1 is a right side view of a nozzle for floor cleaner showing our new design;

FIG. 2 is a front view thereof;

FIG. 3 is a left side view thereof;

FIG. 4 is a rear view thereof;

FIG. 5 is a top view thereof;

FIG. 6 is a bottom view thereof; and,

FIG. 7 is a front-right-top perspective view thereof.
